STACY B. HASELTINE, OF CHICAGO, ILLINOIS, ASSIGNOR TO W. H. MINER, INC., OF CHICAGO, ILLINOIS, A CORPORATION OF DELAWARE

DRAWBAR AND YOKE CONNECTION

Application filed April 18, 1927. Serial No. 184,501.

This invention relates to improvements in drawbar and yoke connections.

One object of the invention is to provide a simple efficient means for connecting the drawbar and draft yoke of a railway draft rigging, wherein ready attachment and detachment of the drawbar is provided for.

Another object of the invention is to provide means for detachably connecting the drawbar to the yoke of a railwa draft rigging, including a holding element wherein the butt end of the drawbar co-operates with the holding element to prevent displacement of the latter and lock it to the yoke.

A more specific object of the invention is to provide a means for connecting the drawbar to the yoke wherein the drawbar is held attached to the yoke by a locking element insertable and removable through transverse slots in the head end of the yoke which slots are off-set with respect to supporting means for the element in the yoke whereby the locking element when in position is disposed out of line with the slots and held by the butt of the drawbar to prevent displacement of the locking element transversely of the yoke and drawbar, together with means on the locking element and the yoke which inter-engage and prevent movement of the locking element with the drawbar under operative conditions.

Other objects and advantages of the invention will more fully and clearly appear from the description and claims hereinafter following.

In the drawing, forming a part of this specification, Figure 1 is a side elevational view of a drawbar and yoke illustrating my improvements in connection therewith. Figure 2 is a horizontal sectional view corresponding substantially to the line 2—2 of Figure 1. And Figure 3 is a transverse vertical sectional view corresponding substantially to the line 3—3 of Figure 1, showing the butt of the drawbar in dotted lines.

As shown in the drawings, my improvements comprise broadly: A yoke A; a drawbar B; and a locking element C.

The yoke A has the usual upper and lower

arms 10 and 11 and a rear connecting piece 12. At the forward end, the yoke is provided with a hooded head 13 having vertically disposed spaced side walls 14—14, a top wall 15, and an inclined bottom wall 16 forming an extension on lower arm 11 of the yoke, and which provides a support for a portion of the locking element C herein-after referred to. The top wall 15 at the outer end thereof is provided with a down-turned flange section 17 which presents a short vertical shoulder adapted to co-operate with the drawbar butt. The forward ends of the walls 14—14, and the bottom wall 16, are provided with forwardly projecting spaced extensions 18—18, and said extensions and portions of the side walls 14—14 are provided with transversely aligned slots 19—19, each of which is substantially ovate in form and disposed at an angle with reference to the longitudinal axis of the yoke and at an angle to the top surface of the inclined wall portion 16, providing abutment surfaces 20—20 which co-operate with the locking element C in a manner herein-after referred to.

The drawbar B is of the usual form and has an enlarged butt end 21 which is shouldered at the top and bottom as indicated at 22—22. The upper shoulder 22 is adapted to engage behind the flange 17 at the top of the yoke to prevent outward movement of the drawbar when the parts are locked in assembled relation. The opening at the forward end of the hood between the flange 17, the bottom wall 16, and the extensions 18—18, is of such a size as to permit the insertion of the drawbar butt through the front end of the yoke.

The locking element or block C is in the form of a relatively heavy plate-like member having an upstanding transversely disposed flange 23, and a bottom wall 24 disposed at substantially right angles to the flange 23, the locking element C being insertable transversely of the yoke through the slots 19—19, and said element is provided with substantially ovate end portions 25—25 which loosely fit in the slots 19—19. The upstanding flange 23 presents a transverse

rear abutment face adapted to co-operate with the lower abutment shoulder 22 of the drawbar B. The block C is insertable transversely of the yoke through the slots 19—19 to such position that the same may be rotated about its longitudinal axis to dispose the wall 24 between the abutment portions 20—20 of the side walls 14—14 of the hood, the ends of the locking element bearing 5 against the walls of the extensions 18—18 which define the forward portions of the slots 19—19, the locking element being thus held against movement in a direction length-wise of the yoke, and due to the disposition of the wall 24 between the abutment portions 20—20 relative lateral movement of the locking element with respect to the yoke is prevented. The end portions 25—25 are provided with portions forming strengthening webs 26—26, which tie together the flange 23 and wall 24 and which, together with said flange and wall, define a recess to accommodate the lower shoulder 22 on the butt of the drawbar.

10 As is well-known in the art, the yoke A is adapted to accommodate the usual shock absorbing mechanism employed in railway draft riggings, the shock absorbing mechanism being usually associated with front and rear followers which co-operate with stop lugs on the draft sills, the followers being also disposed within the yoke and co-operating respectively with the butt end of the drawbar and the abutment surface 27 of 15 the rear section 12 of the yoke. It will be evident that when the yoke has the shock absorbing mechanism and followers assembled therewith, the drawbar will be yieldably maintained in its outer-most position as shown in Figure 1, thereby holding the butt of the drawbar seated in the recess of the locking member C, so that displacement 20 of the locking element in a direction to bring about disengagement of the ends of the wall 24 with the abutment portions 20—20 is prevented.

25 In assembling the drawbar B with the yoke A the butt of the drawbar is passed through the opening at the forward end of the hood of the yoke. Due to the fact that the bottom wall 16 is inclined by tilting the drawbar with respect to the longitudinal axis of the yoke, the drawbar butt will pass freely through the hood until the butt 30 section of the drawbar is disposed entirely within the hood. The drawbar is then straightened up with respect to the yoke moved rearwardly within the yoke a sufficient distance for the lower abutment shoulder 22 to clear the rear ends of the slots 19—19 in the side walls of the hood. It will be evident that when the drawbar butt is in the last named position, the locking block or element C may be freely inserted 35 in a transverse direction through the slots 19—19, and turned in a clockwise direction to engage the rear portion of the wall 24 between the abutment portions 20—20 on the side walls of the hood. When the drawbar yoke has been thus far assembled, the drawbar is pulled forwardly locking the lower portion of the butt within the recess of the locking block and the lower shoulder 22 against the flange 23 on the locking element and the upper shoulder 22 against the shoulder 17 on the upper arm of the yoke. It will be evident that the locking block will thus be positively held against transverse displacement and that outward movement of the drawbar will be limited by engagement with the shoulders 22 of the butt section engaging the flange 17 at the upper side of the hood and the flange 23 of the locking block C. With the draft gear assembled within the yoke as heretofore explained, the drawbar will be yieldingly maintained in its outermost position, thereby effectively interlocking the drawbar with the locking block to prevent lateral displacement of the latter, the locking block holding the drawbar assembled with the yoke. By reason of the inter-engagement of the ends of the wall 24 with the abutments 20—20 on the walls 14—14 of the hood, tilting or lateral movement of the locking element C, which would 40 occur due to swinging movement of the outer end of the drawbar when rounding a curve, is prevented, and the locking element forms in effect a part of the yoke, sufficient clearance being provided in the recess of the locking element to permit tilting of the butt of the drawbar relative thereto, and by this arrangement the opposite ends of the locking element at all times bear substantially equally upon the walls of the extensions 18—18 defining the forward portions of the slots 19—19.

45 While I have herein shown and described what I consider the preferred manner of carrying out the invention, the same is merely illustrative, and I contemplate all changes and modifications which come within the scope of the claims appended hereto.

50 I claim:

1. In a device of the character described, the combination with a drawbar having a shouldered butt; of a yoke having a hood section at one end adapted to receive the shouldered drawbar butt, the side walls of said hooded section being provided with openings adapted to receive a locking block; a removable shouldered locking block disposed transversely of the hood and extending through said openings, said shoulder being adapted to engage the shoulder of the drawbar butt to hold the drawbar assembled with the yoke, said block having portions adapted to co-operate with inter-engaging portions of said yoke to prevent lateral dislodgment of said locking block with respect 55 to the drawbar.

to said yoke and said butt, when the parts are in operatively assembled relation.

2. A yoke for draft riggings formed at its forward end with a hooded head providing side walls and a shoulder adapted to co-act with a corresponding shoulder on a coupler butt, the wall of the yoke opposite the shouldered portion being off-set, said side walls being provided with elongated slots disposed at an angle to the off-set wall; and a locking member provided with a shoulder adapted to co-act with the corresponding shoulder of the drawbar butt, and having an angular extension thereon, said member being insertable through said slots and rotatable to dispose the angular portion between the side walls of said head to prevent accidental removal of said locking block.

3. In a device of the character described, the combination with a yoke having side walls provided with openings; of a drawbar having a T-headed butt end; and a locking element, said locking element having a supporting surface for said T-headed end of the drawbar, said locking element detachably connecting the drawbar to the yoke and being assembled with the yoke by lateral insertion through said openings and being tiltable when in position in the yoke to bring the supporting surface thereof into operative position with respect to the T-headed end of the drawbar, said locking element and yoke having co-operating means thereon effective when in operative position to prevent lateral displacement of said element with respect to the yoke, thereby preventing removal of said element in a lateral direction from the yoke, said element having abutment means thereon co-operating with a T-headed end of the drawbar to limit outward movement of the drawbar with respect to the yoke.

4. A hooded yoke for draft riggings, formed at its forward end to receive a drawbar butt therewithin; and a removable locking block adapted to engage a shoulder on the drawbar to limit outward movement of the latter, the hood of said yoke having openings at opposite sides to receive the locking block and through which said block is insertable, the front walls of said openings limiting forward movement of the block, said block having a reduced portion which, when the block is tilted to operative position, engages between the side walls of the hood to prevent removal of the block in a transverse direction with respect to the yoke.

5. In a device of the character described, the combination with a yoke; of a drawbar having the butt end thereof fitted within the head of the yoke; and means for detachably connecting the drawbar and the yoke, including a locking element, said yoke

being provided with transversely aligned openings adapted to receive the locking element, and also having means thereon co-operating with said locking element to hold the same against displacement longitudinally of the yoke, said openings permitting bodily insertion and removal of said locking element transversely of the yoke, said locking element having an offset portion having shouldered engagement interiorly with the opposite side portions of the head of the yoke, thereby preventing relative lateral movement of said locking element, with respect to the yoke during operative movements of the drawbar butt.

6. In a device of the character described, the combination with a hooded yoke provided with side walls, having a shoulder thereon, said side walls having slots to permit insertion of a locking member; of a shouldered drawbar butt; and a locking member provided with an extension, said locking member being bodily insertable into said yoke through said slots and provided with a transverse vertical wall defining a shoulder corresponding to said first-named shoulder, said shoulders co-operating with the shoulders of the drawbar butt to limit outward movement of the drawbar, said locking member being tiltable after insertion to support the drawbar butt and to dispose the extension of the member between the solid portions of said side walls to prevent lateral movement and tilting of the locking member under operative conditions, said locking member having side extensions together with said transversely disposed vertical wall, defining a recess adapted to receive the shouldered portion of the drawbar butt, said extensions embracing the shouldered portions at opposite sides and said vertical wall engaging the shoulder of said portion.

In witness that I claim the foregoing I have hereunto subscribed my name this 14th day of April, 1927.

STACY B. HASELTINE.
